UNITED STATES PATENT OFFICE.

JEROME IRWIN COLEN, OF MOUNT VERNON, NEW YORK.

BICYCLE-RACK.

1,232,501.

Specification of Letters Patent. Patented July 10, 1917.

Application filed June 22, 1916. Serial No. 105,206.

To all whom it may concern:

Be it known that I, JEROME IRWIN COLEN, a citizen of the United States, residing at Mount Vernon, in the county of Westchester 5 and State of New York, have invented a new and useful Bicycle-Rack, of which the following is a complete, clear, and exact description.

My invention relates to bicycle racks of 10 a kind suitable for supporting bicycles under conditions for conserving space, holding the bicycle firmly in position, and enabling it to be released quickly and with comparatively little effort upon the part of the operator.

More particularly stated, my invention comprehends a rack from which the bicycle is suspended by its front wheel, in such manner that the bicycle is by its own weight 20 held steadily in a fixed position, from which it can be released in an instant by merely pulling a cord for the purpose.

My invention further contemplates, for the purposes above indicated, the use of a 25 number of separate racks, each being a unit complete within itself, so that any number of such units can be placed together in practically the form of a single rack of large size, each unit of the rack being disposed 30 in an elevated position, preferably near the ceiling of a room, so that the bicycles occupy a portion of the room not otherwise likely to be occupied.

Reference is made to the accompanying 35 drawing forming a part of this specification, in which like letters indicate like parts in all of the figures.

Figure 1 is a perspective of a number of 40 my improved racks, as used for supporting bicycles.

Fig. 2 is a view partly in elevation and partly broken away, showing one of the racks.

Fig. 3 is a section on the line 3—3 of Fig. 45 2, looking in the direction indicated by the arrows.

Fig. 4 is a perspective of a block forming a part of the rack.

Fig. 5 is an elevation of a suspension pin 50 and the spring associated with such pin for normally holding it in a predetermined position.

Fig. 6 is a fragmentary vertical section

somewhat similar to Fig. 3 but made upon a smaller scale and showing a larger portion 55 of the bicycle.

A wall is shown at 7 and a ceiling at 8. Engaging this wall and ceiling is a rack which comprises all parts shown in Fig. 2. A pair of end bars 9 are connected with a 60 ceiling plate 10 and a wall plate 11, the ceiling plate being provided with holes 12 and the wall plate being similarly provided with holes 13. Screws 14, 15 extend through the holes 12, 13 in order to secure the rack 65 to the ceiling and to the wall.

A pair of flat cross bars 16, 17 extend from the ceiling plate 10 to the wall plate 11 and are parallel with each other. The ceiling plate 10 is provided with a thickened portion 18 and the wall plate 11 is similarly provided with a thickened portion 19, these two thickened portions each being located between the cross bars.

A guide block 20 is provided with holes 75 21 through which extend screws 22, the latter engaging the cross bar 17 and holding the guide block thereupon.

The guide block 20 is provided centrally with a hole 23, and extending through this 80 hole is a pin 24. This pin also extends through holes 25 with which the cross bars 16, 17 are provided.

A tensile spring 26 of spiral form encircles the pin 26, and is provided with an 85 end portion 27 which extends diametrically through the pin. The spring 26 is further provided with an end portion 28 which may fit into a groove 28^a in the guide block 20, or otherwise held in position. The pin is 90 provided with an eye 30, and secured to this eye is a flexible connection 31, in this instance a cord, which is threaded through a hole 32, and hangs downward. The cord is provided at its lower end with a handle 32.

The operator, by grasping the handle 32 and pulling upon the cord, stretches or extends the spring 26 and thus causes the pin 24 to move to the right according to Fig. 2, so as to clear the space between the cross 100 bars 16, 17. When the pull upon the cord is relaxed the spring 26 retracts the pin 24 to normal position, indicated in Fig. 1. Normally the pin 24 extends across the space between the cross bars 16, 17.

A bicycle is shown at 33, its front wheel

appearing at 34 and its rear wheel at 35. The hub of the front wheel appears at 36, and is of course located at the proximate center of the wheel.

5 The cross bars 16, 17 are spaced apart a sufficient distance to accommodate the front wheel of the bicycle.

10 The bicycle may be suspended from the pin 24 and parts associated therewith, as indicated in Figs. 1, 3 and 6. The pin 24 is so located relatively to the wall 7 that when the bicycle is suspended as indicated the point of suspension of the bicycle—that is, the location of the pin 24—is a little closer 15 than the hub 36 to the wall 7. Thus, the weight of the front wheel, and indeed the weight of the entire machine, tends to cause the front wheel to swing bodily upon the pin 24 as a center, so that the front 20 wheel is pressed toward the wall 7, and against the thickened portion 19 of the wall plate 11.

25 Again, all the rear portion of the bicycle tends to swing upon the hub 36 of the front wheel as a center, so that the rear wheel is pressed into engagement with the wall 7. Both the front wheel and the rear wheel are thus held in stable equilibrium, as much so 30 as if the bicycle rested in its usual horizontal position, with both of its wheels resting heavily upon the ground.

35 Such being the case, the bicycle is unable to dangle or to twist around if disturbed by any ordinary cause, such as the wind blowing or a person accidentally brushing against the machine.

The operation of my device is as follows:

When the operator wishes to dispose of his bicycle for the time being, he lifts the 40 machine with the front wheel upward, and inserts the front wheel between the cross bars 16, 17 and at the same time grasps the ring 32 and pulls upon the cord 31. This moves the pin 24 to the right according to 45 Fig. 2, so that the rim of the front wheel passes upwardly between the holes 25. The cord then being relaxed the spring 26 retracts the pin 24 to normal position, the pin being thus thrust through the front 50 wheel of the bicycle. Thus the bicycle remains suspended from the pin, yet in a condition of stable equilibrium as above explained.

Any number of machines may thus be sus-

pended or stored, as the separate units of 55 the system may be multiplied indefinitely.

I do not limit myself to the precise mechanism shown, as variations therefrom may be made without departing from the spirit of my invention.

60

I claim:

1. In a device of the character described the combination of a pair of cross bars adapted to be secured to a wall and extending parallel to each other in a direction 65 oblique relatively to said wall, said cross bars being spaced apart in order to permit the front wheel of a bicycle to be thrust between them, and a supporting pin mounted upon said supporting bars and movable relatively thereto in order to be thrust through said wheel and withdrawn therefrom, said supporting pin being so positioned relatively to said wall that said bicycle, when suspended from said pin thus thrust through 70 said front wheel, is by its own weight forced horizontally into firm engagement with said wall.

2. In a device of the character described, the combination of a ceiling plate, a wall 80 plate, a pair of cross bars extending from said ceiling plate to said wall plate and disposed parallel to each other, said cross bars being spaced apart to permit the front wheel of a bicycle being thrust between them and 85 being provided with holes in registry with each other, a pin slidably mounted within said holes and adapted to be thrust through said wheel and withdrawn therefrom, a spring for retracting said pin to its normal position, and a flexible connection secured to said pin in order to move the same from its said 90 normal position.

3. As an article of manufacture a rack comprising a ceiling plate, a wall plate, a 95 pair of end bars extending from said ceiling plate to said wall plate, a pair of cross bars extending from said ceiling plate to said wall plate, a pin mounted upon one of said cross bars and movable for the purpose of 100 engaging and disengaging the other of said cross bars, a flexible connection secured to said pin for moving the same, and a spring connected with said pin and with one of said cross bars for the purpose of retracting said 105 pin into a predetermined normal position.

JEROME IRWIN COLEN.
